UNITED STATES PATENT OFFICE

EDWARD KOEGER, OF CHICAGO, ILLINOIS

ABDOMINAL TRUSS

Application filed June 18, 1927. Serial No. 199,827.

My invention relates to trusses for the relief, and to assist in the treatment of hernia.

One object of my invention is to provide an improved truss which will give effective and comfortable support to the hernia. It further provides a belt or appliance having a stay-piece to which a hernial retention pad may be adjustably attached and supported and further to provide means by which, when the belt is adjusted to the wearer, the retention pad will always be so maintained at the hernial opening that extrusion will be made practically impossible.

The principles of my invention are illustrated in the drawings in which Fig. 1 represents a perspective view of my improved apparatus substantially as applied to the body of the wearer; Fig. 2 is a rear view thereof; Fig. 3 represents the structure shown in Fig. 1 when open for application to the figure; Fig. 4 is a central longitudinal section of the front portion of the apparatus, as indicated on line 4-4 of Fig. 1; Fig. 5 is a cross-section of Fig. 4 on the dotted line 5-5; Fig. 6 represents a stay-piece and hasp by which the pad is applied; and Fig. 7 is a rear view of a hernial pad which is adapted to be used with my device.

Further describing my invention with reference to the drawings in which like characters of reference denote like parts throughout: Numeral 1 represents one portion of a belt, preferably of non-elastic webbing; while 1' represents the other portion of the same belt, being preferably made of elastic fabric, which portions taken together are of sufficient length to encircle the body of the wearer. They are also of such width and substantial fabric as to provide a stable foundation for the elements to be attached thereto and which are hereinafter described.

The primary adjustment for length should be made in connection with a back pad 4 having loops 5, 6 and 7 through which the belt members 1 and 1' may be passed so as to lie smoothly on the pad and be adjusted to length by means of the buckle 8. The free end of the portion of the belt indicated by numeral 50 1 should be encased in a leather casing having

the walls 10 and 11 to which it is secured by stitching 12.

The self-adjusting stay-piece is shown in Fig. 6. It consists of an elongated metal foundation plate having a body portion 15, a head portion 16 and a flange portion 17 against which is adapted to rest the free edge of the leather casing sewed to the portion 1 of the belt. A portion 18 may be cut away from the body portion 15 intermediate the ends thereof and rolled to form an eye 19. Hinged to the eye 19 by means of a pintle 22, or in any other suitable manner, is a hasp 20 having a pair of spaced ears 21 at one end thereof and which are adapted to receive between them the eye 19. The major portion of the hasp 20 may be curved as shown in Figs. 3 and 4 to provide an inner concave face of slight curvature for a purpose to be hereinafter described. The outer and free end of the hasp is relatively broad and is provided with an outwardly facing groove or depression forming a looped hook 23. The body portion 15 of the foundation plate is provided with a longitudinal slot 24 through which is adapted to pass a rivet or any other suitable means for securing said plate to said belt, said plate being further secured in said leather casing by means of the stitching 12 thereof, or in any other suitable manner.

The head portion 16 of the stay piece is provided with a transverse slot 28 through which is extended an adjustment bolt 29 having a slotted head 30 and a flange 31 therebelow, which is adapted to seat on the face of the head 16. A truss pad 32 of any desired form has an internal head 33 within which, upon the inner face 34 thereof, is rigidly secured an elongated guideway 34' having slidably mounted therein a nut 35 which is threaded to receive the end of the adjustment bolt 29. It will be observed that, in attaching the hernial pad to the inner side of the belt below the stiffening head forming a portion thereof, any desired portion of the said pad may be brought into any desired relation with the belt itself; and, when in such position, the application to the patient should be made. A suitable piece of rubber 37 having a longitudinal opening should be placed over the adjustment

bolt 29, as shown in the drawing, and it is further noted that for further adjustment, a pin 38 is provided on the head portion 16 upon which the rubber block 37 may be adjustably placed, as indicated by the dotted lines at 37', thus allowing for pressure to be applied to various points of the pad. The elastic portion of the truss 1' is provided with a link 39 and a loop 40, adapted to be engaged by the 10 looped hook 23 on the free end of the hasp 20.

In applying the device, the hernial pad should be placed in approximately operative position with one hand, while the relatively elastic section 1' is drawn around the body 15 with the other hand bringing the loop 40 under pull of the elastic webbing into engagement with the looped hook 23 on the hasp.

When in this operative position, it will be 20 noted that the hasp bears directly on the adjustment screw 29 or 38 as the case may be, which results in a thrust on the pad at right angles thereto, thus avoiding at all times the possibility of the hernia pad being displaced 25 or moved out of the hernial opening. Further it will be noted that by providing a concave inner face for the hasp, not only is a larger bearing surface obtained between the hasp and the resilient means, but also a 30 direct thrust is assured even when the belt is not flat against the body of the wearer.

I claim:

1. A surgical truss comprising a body band, a hernia pad, a stay-plate secured to one end 35 of said band, means mounted on and extending through and in transversely adjustable relation to said stay-plate and connected with said pad, for adjustably securing the pad in position upon the inside of the stay-plate, a 40 hasp hinged to said stay-plate and adapted to bear against said securing means, for pressing said stay-plate and pad inward with respect to the body band, and means for connecting the free end of said hasp with the 45 opposite end of the body band.

2. A surgical truss comprising a body band, a stay-plate secured to one end of said band, a hernia pad, pad-securing means mounted on and extending through and in adjustable 50 relation to said stay-plate, means for connecting said securing means in transversely adjustable relation to the said pad, pressure-applying means mounted on the outside of and in hinged relation to said stay-plate and 55 adapted to bear against said adjustable pad-securing means, and tending to press said stay-plate and pad inward with respect to the body band, and means for connecting the free end of said hinged pressure-applying 60 means with the other end of said body band.

3. A surgical truss comprising a body band provided with fastening means on one end thereof, a stay-plate secured to the other end of said band and provided with a transversely elongated opening therein, a hernia 65

pad, a securing pin extending through said opening and in transversely adjustable engagement with said stay-plate, for adjustably securing said pad upon the inner side of said stay-plate, means for connecting said securing pin in adjustable engagement with said pad, means hinged to said stay-plate and adapted to bear against said adjustable pad-securing means at one point and against said stay-plate at another point on said hinged 70 means, for applying pressure to said stay-plate and pad respectively at different points concurrently, to cause the pad to be pressed inward, and means for connecting the free end of said hinged member with said first-mentioned fastening means.

In witness whereof, I have hereunto set my hand at Chicago, Illinois, this 11th day of June, 1927.

EDWARD KOEBER.
